UNITED STATES PATENT OFFICE.

MORRIS FALK, OF FITCHBURG, MASSACHUSETTS.

DISK LOCK.

Application filed September 10, 1928. Serial No. 304,994.

This invention relates to that type of disk locks in which the plug is provided with several disks normally pressed outwardly by individual springs.

The principal objects of the invention are to provide simple and inexpensive means whereby the disks are prevented from being forced out of the plug when the plug is removed from the lock and particularly when the plug is shipped and prepared to introduce into the lock and also to provide a construction in which, in spite of the fact that the disks cannot be accidentally discharged, they can be removed by the exercise of care.

Reference is to be had to the accompanying drawings in which

Fig. 1 is a side view of a plug constructed in accordance with this invention showing the disks in position;

Fig. 2 is a sectional view on the line 2—2 of Fig. 1;

Fig. 3 is a view similar to Fig. 2 showing the key in place; and

Fig. 4 is a side view of one of the disks.

A great deal of difficulty has been encountered by manufacturers, particularly automobile manufacturers, in the handling of these disk locks. The disks are spring-pressed and there is nothing to prevent the springs pressing out and discharging them from the plug when the plug is not in the lock. These plugs are shipped separately with the disks in place and they have to be held there by a temporary cylinder placed over the plug and sometimes they are held in place by winding wire around them. If the assembler accidentally lets one of these disks loose it will pop out of the plug and thus waste time in the assembling. If two or more of them should come out, the combination might be lost if they were not put in correctly.

This invention is designed to obviate these difficulties. The invention is shown as applied to a plug 12 having eccentricities 15 at the end, the plug being of the ordinary kind slotted in the usual way. It is provided with a series of disks 24 in slots in the plug, each disk being pressed outwardly by a spring 27.

In this case a slit 28 is cut in the disk and a projecting hook 29 left thereon engages a shoulder 31 in the slot in the plug 12 when the spring forces the disk out so as to hold the disk in the position shown in Fig. 1. On account of the slit 28 and the

disk being of resilient material, it is possible to move the disk over carefully and get it out of the plug in spite of this hook 29. However, that requires some pressure and movement of the parts so that the disks cannot get out of place accidentally. Therefore these plugs can be assembled with the disks in them and shipped with no external means for holding the disks in position. This gives the automobile manufacturer the opportunity of having these plugs assembled with no chance of losing time by the disks coming out and solves a very important problem for him.

In Fig. 3 I have shown the key 30 in place showing how it forces the disk down into the plug and keeps its surfaces within the circumference thereof. This is, of course, the usual practice.

Although I have illustrated and described only one form of the invention I am aware of the fact that modifications can be made therein by any person skilled in the art without departing from the scope of the invention as expressed in the claims. Therefore, I do not wish to be limited in this respect but what I do claim is:—

1. In a lock of the character described, the combination with a plug having slots therein and a series of spring pressed disks in the slots, each disk having yielding but integral means at the side thereof for preventing its accidental removal, and for permitting intentional removal.

2. In a lock of the character described, the combination with a plug having slots therein and a series of spring pressed disks in the slots, each disk having a yielding integral hook extending from one edge for engaging a shoulder in the slot to prevent the accidental removal of the disk, and for permitting intentional removal.

3. The combination with a plug for a lock, said plug having a disk slot therein, of a disk in said slot, the slot having a shoulder and the disk being provided with an outward projection adapted to engage the shoulder when the disk is pushed out and a spring for engaging the disk on the other side and pushing the projection against the shoulder.

4. The combination with a plug for a lock, said plug having disk slots therein, of disks in said slots, the slots having each a shoulder and the disks being provided with a yielding integral hook adapted to engage

the shoulders when the disks are pushed out and springs for engaging the disks and pushing the hooks against the shoulders.

5. As an article of manufacture, a disk 5 tumbler for a lock having parallel lateral sides and provided with a shoulder on one side for engagement by a spring and a yielding hook on the other side and near the op-

posite end, the disk having a portion extending across it at the bottom but having a slit 10 entirely through it under said hook, leaving the hook free at the bottom:

In testimony whereof I have hereunto affixed my signature.

MORRIS FALK.
